United States Patent Office.

JONATHAN DAVID, OF EAST ENTERPRISE, INDIANA.

Letters Patent No. 79,109, dated June 23, 1868.

IMPROVEMENT IN FARM-GATE.

The Schedule referred to in these Letters Patent and making part of the same.

TO ALL WHOM IT MAY CONCERN:

Be it known that I, JONATHAN DAVID, of East Enterprise, in the county of Switzerland, and State of Indiana, have invented new and useful Improvements in Farm-Gates; and I do hereby declare that the following is a full, clear, and exact description thereof, which will enable those skilled in the art to make and use the same, reference being had to the accompanying drawings, forming part of this specification.

This invention has for its object a cheap and convenient farm-gate, one not liable to get out of order, and which, by reason of the front stile rising when the bolt is drawn back, avoids all obstructions to its free swing, such as snow-drifts, frozen clods of earth, or the ultimate sagging downwards of the front stile, resulting from the constant strain tending to that end, so often found in large gates.

Another important object is to construct the gate so that it may be hoisted vertically to a limited height, so that the smaller domestic animals may pass under without permitting the larger ones to do so.

Figure 1 is an elevation of the gate, closed.

Figure 2 is a view of the same, hoisted.

Similar letters of reference indicate corresponding parts.

A and A' are the gate-posts. In A is cut the mortise or socket, s, for the bolt G. C is the hanging stile, D the top rail, and E a double brace. These form a species of crane. The rails, $a a' a'' a'''$, are hung on wooden pins, 1 2 3 4, which pass through the stile C', said stile being slotted for the admission of the rails. These rails, pass through the double brace E, and are hung at their other ends on the pins 6 7 8 9, in the double-front stile C. H is a double strip, pinned to the upper and lower rails, to serve as a guide for the said rails, and for the bolt G. F is the lever for operating the bolt; it is forked for about two-thirds of its length, and passed over the top rail D. The pin i passes through the forks of the lever and the rail a, which forms a fulcrum. Another pin, near the lower end of the lever, attaches it to the bolt G. c is a sheave in the crotch of the lever F, and which rolls on the upper edge of the top rail, D, to lessen the friction.

When the gate is to be opened, the lever is thrown forward, as in the red lines, which draws the bolt from its socket, and, at the same time, lifts the front stile C, and the forward ends of the rails sufficiently to clear obstructions, (see red lines.)

The stile C' is hung to the supplementary post B. This post is grooved and slotted for the reception of the screws or bolts, n n, (see fig. 2,) said screws passing through the slot g in the post B, and firmly screwed into the post A', to serve as guides for the post B in its vertical movement, as shown, (fig. 2.)

This movement is accomplished by means of the circular cam J, provided with the crank-pin d, and attached to the post A' by the screw m, or equivalent device.

This cam, in revolving, operates against the pin b, in the post B, lifting the said post vertically, and through it the gate, as is clearly shown in the figure.

In the front stile, C, is a hole, 5. When it is desired to keep the forward end of the gate raised, the lower portion of the gate is lifted until the said hole comes above the top rail, D, when a suitable pin is inserted, and the gate is held up, as shown, (red lines, fig. 2.)

At t, fig. 2, is one of a series of holes in the post A', for the insertion of check-pins, to keep the cam J in any required position, and consequently the gate at the proper height.

One important feature in this gate is its cheapness and simplicity of construction. Being made almost entirely of wood, any farmer can construct it for himself.

Having thus described my invention, what I claim as new, and desire to secure by Letters Patent, is—

1. The arrangement of the forked lever F and sheave c with the articulation of the said lever on the bar a, by means of which the front stile, C, is lifted simultaneously with the drawing back of the bolt G, in the manner and for the purposes substantially as described.

2. Hoisting the gate by means of the cam J and pin b, through the medium of the slotted supplementary

post B, and guide-bolts or screws, n n , or their equivalents, when used substantially in the manner and for the purposes as set forth.

3. The articulated arrangement of the bars a a^1 a^2 a^3 in the stiles C and C', on the pins, 1 2 3 4 6 7 8 9, by means of which the forward end of the gate may be lifted, and kept up by a pin inserted in the hole 5, over the upper bar D, in the manner as specified.

Witness my hand, this 6th day of April, 1868.

JONATHAN DAVID.
